CLAIM

The ornamental design for a charger, as shown and described.

DESCRIPTION

FIG. 1 is a top perspective view of the front of a charging base station showing a (not claimed) mouse on top of it.

FIG. 2 is a top perspective view of FIG. 1, showing the charging base station from front with a (not claimed) power cable plugged in.

FIG. 3 is a top perspective view showing the back of FIG. 2.

FIG. 4 is a top view of FIG. 2.

FIG. 5 is a bottom view of FIG. 2; and,

FIG. 6 is a rear view of FIG. 2.

The broken lines shown in the drawings are included for the purpose of illustrating environmental structure and form no part of the claimed design.
